UNITED STATES PATENT OFFICE

97,480

DESIGN FOR AN OVERSHOE

Louis J. Golden, Highland Park, Ill.

Application January 23, 1935, Serial No. 55,016

Term of patent 3½ years

To all whom it may concern:

Be it known that I, Louis J. Golden, a citizen of the United States and resident of Highland Park, in the county of Lake and State of Illinois, have invented a new, original, and ornamental Design for an Overshoe; of which the following is a specification, reference being had to the accompanying drawing, forming a part thereof.

Figure 1 is a view in perspective of an overshoe showing my new design;

Fig. 2 is a view in perspective of the underside thereof; and

Fig. 3 is a side elevational view of the same in open position slightly on an enlarged scale.

The dominant feature of my invention comprises the closing flap which is stitched to the

rear edge of one side of the overshoe along substantially the full length of said rear edge with one side edge of said flap extending diagonally across the opposite side of the shoe to which it is secured when in closed position by a conventional slide fastener with the free end of the flap secured in overlapping position to the first mentioned side adjacent the upper edge thereof.

I claim:

The ornamental design for an overshoe as shown and described.

Signed at Chicago, in the county of Cook and State of Illinois, this 14th day of December, A. D. 1934.

LOUIS J. GOLDEN.
